VERTICAL TAKE-OFF AIRCRAFT

Robert John Lang, 16840 Chatsworth St.,
Granada Hills, Calif. 91344

Filed Sept. 16, 1966, Ser. No. 3,890

Term of patent 14 years

(Cl. D71—1)

FIGURE 1 is a plan view of the vertical take-off aircraft;

FIG. 2 is a side-elevational view of the vertical take-off aircraft; and

FIG. 3 is a front view of the vertical take-off aircraft.

I claim:

The ornamental design for a vertical take-off aircraft, as shown.
